UNITED STATES PATENT OFFICE.

GEORGE H. MAAS, OF MILWAUKEE, WISCONSIN.

MEANS OF ATTACHING THE HEADS OF GOLF CLUBS TO THEIR STICKS.

Application filed May 23, 1923. Serial No. 640,830.

To all whom it may concern:

Be it known that I, GEORGE H. MAAS, a citizen of the United States, and a resident of the city of Milwaukee, county of Milwaukee, and State of Wisconsin, have invented certain new and useful Improvements in Means of Attaching the Heads of Golf Clubs to Their Sticks; and I do declare the following to be a clear, exact, and complete description thereof, such as will enable others skilled in the art to which the invention pertains to make and use the same, reference being had to the accompanying drawing as illustrating a construction in which my invention has been embodied.

The invention relates to the means employed for connecting the head of a golf club to the shaft or handle thereof, and is applicable particularly to golf clubs in which the head or driving member is shaped from a wooden block.

In effecting such attachment it is customary to bore a tapering hole in the shank of the head, and secure therein the smaller end 25 of the uniformly tapering shaft. In order to avoid an enlargement caused by the upper end of the shank, it is the practice to reduce the shank by a formation which tapers from the head to the end of the shank. In 30 such formation the shank is thinned so that the feather edge at its termination is barely perceptible. Thus a symmetrical structure is produced, tapering from the upper end of the shaft to the point of its smallest exposed diameter, and then gradually enlarged 35 by a tapering formation which is absorbed in the head of the club. In order to effectively secure the head to the shaft it is the customary practice to wind about the stick 40 at the point of union described, strong thread, the winding of which will extend for a suitable distance above and below the line of the smallest diameter before mentioned. By reason of the gauge of the thread used 45 in such winding, there is no appreciable increase in the diameter of the stick in the section so wound. While this method of attachment is ordinarily sufficient and preserves the symmetry of the structure, it is 50 objectionable inasmuch as the thread winding is sometimes damaged and even broken in rough use. Under such circumstances, unless care be taken, the thin feathered edge of the upper shank of the head will become 55 free from confinement by the winding and exposed to damage. Very soon the club

will be reduced to an unserviceable condition and must be discarded as a loss.

My present invention contemplates an improved structure in which the means employed by me for fastening the head of the club to the shaft are such that the liability to damage and destruction heretofore referred to is completely eliminated and this very desirable result is achieved by the application of securing means in a most novel form. In carrying out the invention I apply to the joint, which may be referred to as that point in the length of the club where the shaft enters the shank, a ferrule of peculiar formation and adaptability for the purposes of my invention. The said ferrule is constituted as a tube of plastic material, it possessing the properties of shrinking and hardening when heated or exposed to the atmosphere, and embodying also the characteristic of great durability. After the ferrule has been placed upon the shank and the shaft inserted and secured in the hole, and when the plastic ferrule has become set and hardened, the parts will be found to be firmly united. Suitable finishing operations to remove projecting portions and produce the symmetrical outline so much desired are then resorted to.

The invention will be described in detail later on in this specification, and the novelty will be pointed out in the appended claims.

In the accompanying drawing:

Figure 1 is a view illustrating the striking end of a golf club, showing the lower end of the shaft in elevation and the head partly in elevation and partly in vertical section, with the shank and the ferrule in section.

Fig. 2 is a similar fragmentary view illustrating the portions of the shaft and head in elevation and the ferrule in section.

In the drawing, the numeral 10 indicates the head of a golf stick, the said head being provided with a rearwardly and upwardly extending shank 11 of usual formation, these parts being shaped integrally from a block of wood in the rough. The shank 11 is then proportioned so as to taper from the head with the desired length and diameter. About the shank is fitted a ferrule 12 of plastic material having the properties of shrinking and hardening under exposure, the length of the ferrule exceeding somewhat that of the shank upon which it is

placed. I have found after an experimentation covering more than a year that celluloid in its uncured state is well adapted for the formation of the ferrule, as is also celluloid which has hardened, but which may be softened preparatory to its application to the shank 11.

In order to effect an increased anchorage of the ferrule upon the shank, I may provide the said shank with a suitable super-fiscal recess into which a part of the ferrule may shrink in the drying operation and thus effect a firm union between the parts. In the construction illustrated, I have shown a circumferential recess, 13, as being formed adjacent the shoulder 14, it existing at the intersection of the shank with the head, into which the lower end of the ferrule will contract to form a constriction 15 and make a perfectly tight joint at that point. The shrinkage of the ferrule causes it to engage the shank with a high degree of friction, and with the anchorage afforded by the circumferential groove 13, the ferrule cannot become dislodged and therefore becomes a permanent part of the structure.

When the ferrule has become set upon the shank with the desired degree of hardness, the tapering hole 16 is bored centrally of the shank. The projecting end 17 of the ferrule is then softened so as to become pliable. The pointed end 18 of the shaft 19 is then inserted in the tapering bore 16 and glued therein in its final position. In a little while the end of the projecting ferrule which has been softened to permit the connection of the head to the shaft 19 will shrink and become hardened upon the portion of the shaft encircled by it, a strong frictional engagement being effected between the two parts.

After suitable seasoning, the head of the club is sanded into the desired shape, as is also the ferrule by removing all projecting and uneven surfaces therefrom, so as to produce a symmetrical structure. In such sanding operation the end of the ferrule is reduced so as to taper to a thin edge as indicated at 20, in Figure 1, forming a line of union with the shaft which is barely perceptible to the touch. Severe use, covering a comparatively long period of time, has demonstrated both the serviceability and durability of my improved means of joining the head of the club to the shaft thereof.

It will be observed that in the actual construction the ferrule is adapted to receive at one end the tapered shank of the head of the club and at the other end the uniformly tapered lower end of the shaft, so that in actual use the said ferrule tapers interiorly from each end toward the middle or to the line of the smallest diameter of the parts which it is used to connect. This method of fastening parts together I regard as novel. I have found celluloid to be well adapted

for the purposes of my invention, but it is to be understood that other substances possessing properties which will enable them to be employed in the attainment of the purposes of my invention may be used instead. It will also be within the scope of my invention to assemble the elements of the club in a sequence of operations which is different from that hereinbefore recited. For instance, it will be possible to complete the assembly by inserting the shaft into the bore in head while the ferrule applied to the shank is in its plastic state, thus obviating the preliminary seasoning of the ferrule upon the shank before the shaft is inserted. But the best results are secured by following the steps first outlined.

Having thus described my invention, what I claim and desire to secure by Letters Patent of the United States, is:

1. A golf club comprising a shaft with a tapering end and a head provided with a bore in which the end of the shaft is secured, in combination with a ferrule contracted about the joint between the shaft and head.

2. A golf club comprising a shaft with a tapering end and a head provided with a tapering bore in which the end of the shaft is secured, in combination with a ferrule formed of plastic material and contracted about the joint between the shaft and head.

3. A golf club comprising a shaft with a tapering end and a head bored at one side to receive the said end, in combination with a ferrule formed of plastic material and contracted about the joint to unite the shaft to the head.

4. A golf club comprising a shaft with a tapering end and a head with a tapering shank, the latter being bored to receive the said end, and a ferrule of hardened plastic material covering the joint and uniting the shaft and head.

5. A golf club comprising a shaft having a tapering end and a head with a tapering shank, the latter being bored to receive the said end, and a ferrule tapering interiorly from its ends encircling the shaft and the shank to unite the shaft to the head.

6. A golf club comprising a shaft having a tapering end and a head having a tapering shank in which the said end is secured, and a ferrule of hardened plastic material tapering interiorly from its ends and encircling the parts at the point of their union.

7. A golf club comprising a head having a tapering shank the latter being recessed on its surface, a shaft the tapering end of which is inserted in the shank, and a ferrule of hardened plastic material encircling the shaft and shank at the point of their union and filling the said recess.

8. A golf club comprising a head having a tapering shank, a shaft tapering toward

one end, the said end being inserted in the shank, and a tubular ferrule of hardened plastic material encircling the parts at the point of the convergence of the taper of the shank with that of the shaft, to unite the head to the shaft.

9. A golf club comprising a head having a tapering shank, a shaft tapering toward one end, the said end being inserted in the shank, in combination with a tubular ferrule tapering interiorly from its ends surrounding the parts at the point of the convergence of the taper of the shank with that of the shaft, to unite the head to the shaft.

10 15 10. A golf club comprising a head having

a tapering shank and formed with a shoulder at the intersection of the head and shank, a shaft tapering toward one end inserted in the shank, in combination with a ferrule embracing the shank and seated 20 against the said shoulder, the said ferrule extending beyond the point of convergence of the taper of the shank with that of the shaft and also embracing a section of the latter to unite the head to the shaft. 25

In testimony whereof I have signed my name at Milwaukee this 19th day of May, 1923.

GEO. H. MAAS.
